UNITED STATES PATENT OFFICE.

CLINTON R. HANNA, OF WILKINSBURG, PENNSYLVANIA, ASSIGNOR TO WESTINGHOUSE ELECTRIC & MANUFACTURING COMPANY, A CORPORATION OF PENNSYLVANIA.

LOUD-SPEAKER UNIT.

Application filed May 8, 1925. Serial No. 28,792.

My invention relates to telephone receiver devices and particularly to such devices as are adapted for heavy duty service.

An object of my invention is to provide 5 a telephone receiver device adapted for the translation of substantial amounts of vibratory electrical energy into sounds of substantial volume.

Another object of my invention is to produce 10 a telephone receiver device which is capable of the production of sounds with a minimum amount of distortion.

Another object of my invention is to provide 15 a telephone receiver device having therein an annular magnet in which one pole is upon the inner annulus and the other pole is upon the outer annulus.

Another object of my invention is to produce 20 a telephone receiver device in which the vibratory diaphragm carries minimum magnetic flux.

Another object of my invention is to provide 25 a telephone receiver device in which the steady flux passes through a minimum portion of the diaphragm and in which the vibratory flux passes through a maximum portion of the diaphragm.

Another object of my invention is to provide 30 a telephone receiver device in which the vibratory flux is by-passed through a magnetic circuit other than that of the permanent magnet.

Another object of my invention is to provide 35 a telephone receiver device in which a sound conveying channel is provided concentric with the electromagnet coil.

A further object of my invention is to provide 40 a telephone receiver device having a sound chamber cooperating with a diaphragm in which the sound chamber has the shape of a right cone of low altitude and in which a sound-conveying channel is connected to the apex of the conical space.

In prior construction of telephone receiver 45 devices, attempts have been made to provide devices which are capable of the translation of substantial amounts of voice frequency electrical energy into sounds of substantial volume. Sounds are most conveniently produced by the electromagnetic reaction between a magnetically permeable diaphragm, a steady magnetic flux and a varying flux produced by the current to be translated.

Difficulty has, however, been experienced

in handling sufficient energy to produce an 55 adequate sound volume without serious difficulties from distortion and incorrect translation, which produce sounds different in quality from the original.

The most serious limitation in the ordinary telephone receiver device has been that imposed by the necessity of conveying through the diaphragm the steady flux which is required to prevent doubling of the sound frequency. In order to obtain 60 adequate movement of a diaphragm it must be thin, else its rigidity will prevent sufficient movement, but after it is made sufficiently thin it will carry only a limited amount of magnetic flux without reaching 65 its saturation point. This difficulty is further complicated by the fact that the steady flux must be considerably greater than the maximum varying flux. If, however, the steady flux could be removed from the diaphragm, leaving only the varying flux to pass therethrough, the permeability of the diaphragm is ample for the translation of 70 any reasonable amount of vibratory electric energy.

Other difficulties encountered in the design of telephone receiver devices have been those of providing a sufficient amount of steady flux in a reasonable weight of material and still other difficulties have been encountered in the provision of a sound chamber around the diaphragm of such shape that maximum utilization of vibratory movements of the diaphragm is made.

My invention provides means whereby the 90 steady flux is substantially removed from the diaphragm; only a small annular ring near the center of the diaphragm being subject to the steady flux.

My invention further provides means 95 whereby annular magnets of high coercive force material of the type disclosed in my copending application Serial No. 734,604, filed August 28, 1924, are used. Each of these magnets has one pole at the inner annulus and the other pole on the outer annulus.

My invention further provides tubular pole pieces for the permanent magnets upon which are wound electromagnet coils for 105 the vibratory electric current.

My invention further provides magnetic shunts for the vibratory flux according to

the disclosure of the previously mentioned copending application.

My invention also provides a conical sound space cooperating with the diaphragm, and having a sound conveying channel from the apex thereof. A horn is connected thereto for obtaining maximum response from a diaphragm according to the copending application of Joseph Slepian and myself, Serial No. 690,405, filed February 4, 1924.

Other objects and structural details of my invention will appear from the following description, when read in connection with the accompanying drawing wherein:

Figure 1 is a representation, partially in elevation and partially in axial section of a preferred form of my invention, and a diagrammatic representation of circuits co-20 operating therewith.

Fig. 2 is a plan view of a receiver device embodying a form of my invention; and

Fig. 3 is an enlarged fragmentary sectional view showing the diaphragm and sound chamber.

In Fig. 1, a telephone receiver 1, is shown associated with a horn 2, and connected to a radio receiving system 3. The receiver 1 comprises a pair of tubular elements 4 and 5, clamped together by a threaded ring 8 and have, respectively, a smooth shoulder 6 and a threaded shoulder 7. A pair of annular magnets 9 and 10 are inserted within opposite ends of the tubular sections 4 and 5. These annular magnets may be of material of high coercive force described in my previously-mentioned application, and are magnetized at a suitable stage in the assembly of the device, in such manner that the magnetic poles are upon the respective inner and outer annulæ, and that one magnet has upon its inner annulus a pole of one polarity and the other magnet has upon its outer annulus a pole of the opposite polarity.

A diaphragm 11, of magnetic material, shown in greater detail in Fig. 3, is clamped between the tubular sections 4 and 5, which are also of magnetic material. The tubular pole pieces 14 and 15 are inserted within the inner annulæ of the magnets 9 and 10. These pole pieces are somewhat shorter in length than the members 4 and 5 in order that they may not interfere with the vibration of the diaphragm by contact with it. Upon the pole pieces 14 and 15 are mounted electromagnet coils 16 and 17. The pole pieces 14 and 15 have formed thereon shoulders 18 and 19 slightly less in diameter than the inner diameter of the tubular body members 4 and 5. These shoulders 18 and 19 cooperate with the body members 4 and 5 to serve as magnetic shunts. Filler pieces 21 and 22 of slightly conical annular shape are mounted upon the pole pieces 14 and 15 and adapted to fill the inner ends of the

tubular pieces 4 and 5. The tubular opening through the pole piece 14 is connected to the inlet of the horn 2 and the tubular opening in pole piece 15 is closed by a plug 23.

In the operation of my device, a steady magnetic flux is established by the magnets 9 and 10 through a magnetic circuit consisting of magnet 9, tubular piece 4, the edges of diaphragm 11, tubular piece 5, magnet 10, pole piece 15, annular air gap 24, an annular ring portion of diaphragm 11, an air gap 25 and pole piece 14. An additional magnetic path is provided for the magnet 9 through a portion of base 4 across an air gap to the shoulder 18 and pole piece 14. A similar shunt path is provided for the magnet 10. Still another magnetic path is provided for the flux of coil 16 through a portion of the pole piece 14 to the shoulder 18, a small air gap to the tubular piece 4, diaphragm 11, air gap 25 and back to the pole piece 14. A similar path for the flux of coil 17 is provided.

The steady flux of magnets 9 and 10 passes through a small portion only of the diaphragm 11 and exerts no pull thereon. The coils 16 and 17 are connected to produce opposite magnetization in the ends of the pole pieces 14 and 15. Upon the energization of the coils 16 and 17, flux produced by these coils is caused to pass through the diaphragm in such way as to produce a pull thereon. With current flowing in a given direction it may flow through coil 16 in such direction as to strengthen the flux passing from magnet 9 and also tend to cause flux in the diaphragm 11 between the end of pole 14 and the tubular portion 4. Simultaneously, the same current flowing in coil 17 produces a magnetization in opposition to the flux produced by magnet 10, thereby diverting a portion of its flux through the shoulder 19 and increasing the amount of flux which flows through the diaphragm 11.

As a result of this action, the diaphragm 11 may be attracted towards the pole piece 14 with an intensity varying with the strength of the current flowing. This attraction causes a movement of the center of the diaphragm towards the pole piece. When a vibratory current is passed through the coils, this movement becomes a vibratory movement corresponding to the vibrations of the current. These vibrations move adjacent air, which movement is perceptible as sound.

By this system of construction, flux corresponding only to the flux produced by the varying current in the coils 16 and 17 passes through the greater portion of the diaphragm 11 and, therefore, a much greater strength of varying flux can be employed without reaching the magnetic saturation of the diaphragm than is possible by construc-

tions in which the permanent flux and the varying flux both pass through the diaphragm in the same path.

The filler pieces 21 and 22 restrict the space in which the diaphragm vibrates to such volume that the maximum vibration of the diaphragm will traverse a major portion of it. In consequence, a maximum displacement of air into the tubular centers of the pole pieces is obtained, resulting in a maximum sound amplitude. This sound amplitude is further reenforced by the horn described in my previously mentioned application, whereby maximum loading of the diaphragm is obtained and a maximum efficiency of translation is also obtained. The presence of the plug 23 prevents the egress of sound energy of opposite phase and thereby prevents that loss of energy.

By this means, I am enabled to provide a telephone receiver device which is capable of translating much higher power at much greater efficiency and with much greater accuracy than previous devices.

While I have shown but a single embodiment of my invention in the accompanying drawing it is capable of various changes and modifications therefrom without departing from the spirit thereof and it is desired therefore that only such limitations shall be imposed thereon as are indicated in the prior art or in the appended claims.

I claim as my invention:

1. A telephone receiver device comprising an annular magnet, the outer periphery thereof constituting one pole, the inner periphery thereof constituting the other pole, and a magnetizable case cooperating with said outer pole, and a magnetizable tubular pole piece cooperating with said inner pole and having a magnetic shunt piece extending toward said case, a magnetizable diaphragm, and a magnetizing coil therearound.

2. A telephone receiver device comprising an annular magnet, the outer periphery thereof constituting one pole, the inner periphery thereof constituting the other pole, a magnetizable case cooperating with said

outer pole, a magnetizable tubular pole piece cooperating with said inner pole and having a magnetic shunt piece extending toward said case, and a magnetizing coil therearound and a diaphragm clamped to said case, and adjacent said pole piece.

3. A telephone receiver device comprising a cylindrical magnetizable material case, a diaphragm therein, an annular permanent magnet cooperating therewith, a pole piece attached to the annulus thereof, and a magnetizing coil thereon, said pole piece being tubular for the conveyance of sound vibrations, and a circumferential ridge therearound cooperating with said case to form a magnetic shunt for magnetic flux from said coil.

4. A telephone receiver device comprising a diaphragm, a support therefor, a permanent magnet cooperating therewith, a tubular pole piece between said diaphragm and magnet and an electromagnet coil thereon and a perforated non-conductive disc parallel to and adjacent to said diaphragm, said pole piece being inserted in the perforation therethrough, said tubular pole piece and said perforated disk being adapted to convey, control, and accentuate sound vibrations produced by said diaphragm.

5. A telephone receiver device comprising a diaphragm, a tubular pole piece, a magnetizing coil thereon, a conical, non-conductive non-resonant annular disk adjacent said diaphragm, and surrounding the end of said pole piece.

6. A telephone receiver device comprising a diaphragm, a tubular pole piece, a magnetizing coil thereon, a conical, non-conductive non-resonant annular disk adjacent said diaphragm, and surrounding the end of said pole piece, the edge of said disc being closely adjacent to said diaphragm near the edges thereof, and being distant from said diaphragm by less than $\frac{1}{16}$ the diameter thereof at the annulus thereof.

In testimony whereof, I have hereunto subscribed my name this 29th day of April 1925.

CLINTON R. HANNA.
